UNITED STATES PATENT OFFICE.

FRED RICKS AND ALFRED EDWARD RICHARDS, OF LEICESTER, ENGLAND, ASSIGNEES
TO UNITED SHOE MACHINERY CORPORATION, OF PATERSON, NEW JERSEY, A COR-
PORATION OF NEW JERSEY.

SKIVING MACHINE.

Application filed June 23, 1921. Serial No. 479,836.

To all whom it may concern:

Be it known that we, FRED RICKS and ALFRED E. RICHARDS, subjects of the King of England, residing at Leicester, Leicestershire, England, have invented certain Improvements in Skiving Machines, of which the following description, in connection with the accompanying drawings, is a specification, like reference characters on the drawings indicating like parts in the several figures.

This invention relates to machines for skiving, splitting, or similarly operating upon leather or other sheet material and more particularly to machines for skiving parts of boots or shoes. The illustrative machine in which the invention is embodied is of that type having a cylindrical knife of which the machine shown and described in the specification of United States Patent No. 1,117,541 is an example.

In machines of this type it has been found that with certain classes of work the material is not effectively controlled by the feed roll and presser as it is fed to the cylindrical skiving knife with the result that the skiving knife at times digs into the material and the skived portion of the material is hollowed instead of being flat.

One feature of this invention relates to the provision of certain means whereby the material is effectively controlled as it is fed to the skiving knife, and digging in of the knife and consequent hollow skiving minimized; and, with this in view, the illustrative embodiment of the invention includes a construction and arrangement of presser and feed roll such that the greatest pressure between these parts upon the work occurs at a distance from the edge of the margin being operated upon.

A further feature of the invention is the provision of means in conjunction with a construction and arrangement as just referred to whereby, when an inaccurately skived piece of material is put through the machine a second time, the thin edge of the material will be effectively supported.

In the present machine the presser, unlike that of the patent, is angularly adjustable to vary the inclination of the scarf or bevel produced upon the edge of the work. It is desirable in many instances that when the presser is adjusted angularly to vary the

angle of the bevel upon the work, no bodily adjustment of the presser toward or from the knife should be necessary. In other words, that portion of the presser which is adjacent the edge gage at any time should always be a uniform distance from the edge of the knife irrespective of the angular position occupied by the presser. In the illustrative machine the presser is concave for the greater part of its extent, the concave portion merging into a convex portion at that end of the presser which is adjacent to the edge gage; and the presser is made adjustable about the center of longitudinal curvature of the contour or outline of that portion of the convex portion which is adjacent the knife.

These and other features of the invention, including certain details of construction and combinations of parts, will be described as embodied in an illustrative machine and pointed out in the appended claims.

In the accompanying drawings,—

Fig. 1 is an end elevation, partly in section, of the machine;

Fig. 2 is a side elevation showing parts of the feed and presser mechanisms;

Fig. 3 is a plan view of the feed roll and parts cooperating therewith; and

Figs. 4 and 5 illustrate diagrammatically the operative relationship of the feed roll and the presser and their action upon the work.

Before proceeding to a detailed description of the invention a brief general description of the machine will be given. Fast to a rotatable shaft 6 mounted in suitable bearings in the frame 8 of the machine is a cylindrical knife 10. Located partly inside the knife is a feed roll 12, and above the knife is a presser, herein shown as a roll 14. The presser roll is carried, in a manner presently to be described, at the lower end of a vertically adjustable bar 16 which itself is mounted in an overhanging arm 18. An edge gage 20, adjustably held in place by a thumb-screw 22, serves to guide the work. The mounting of the knife and feed roll of the present machine is or may be substantially the same as that of the patented machine and consequently no further detailed description of the general construction of the machine will be given. It will be understood that the knife and feed roll are ro-

tated continuously and that the material to be skived is fed away from the observer with its edge in contact with the gage 20, the presser being rigidly held, except from rotation, so as to determine the angle of the scarf, and the feed roll yieldingly accommodating itself to the fixed position of the presser.

In the present machine the angle of the 10 scarf is determined by adjusting the presser 14 angularly, said presser being concave substantially throughout its operative face. When, as has hitherto been the case, a concave presser has been employed with a concave feed roll, the presser and feed roll have gripped the work 100 with maximum force only at a single point at the extreme edge of the work. The result of this has been that the work has not been held securely enough 20 in that it has not been crowded or bent into the concavity of the presser; and with the work thus insecurely held the knife has tended to dig into the work to produce a scarf which is considerably curved instead of being, as it should be, approximately straight.

In order to remedy this defect, the feed roll of the illustrative machine is cut away beyond (to the left in the figure) the locality which engages the edge of the work and adjacent the edge gage 20; and, for a short distance away from the edge gage, where the feed roll is opposed by the presser, is reduced in diameter and made cone-shaped as at 24 (see Fig. 4), the smaller diameter of 30 the cone being nearer the edge gage. With a feed roll of this shape it has been found that the work is effectively held against the presser, and the knife is prevented from digging into the work. Apparently this is due 40 to the fact that the maximum pressure upon the work is not at the extreme edge but at a point opposite the concavity of the presser. Referring more particularly to Fig. 4, it will be seen that the maximum pressure is 45 along a line in the plane indicated by the dotted line 26, and that pressure thus localized bends the work into the concavity of the presser. It is along this line or plane that the contour of the feed roll changes abruptly 50 so as to form a sort of ridge or shoulder which bends or breaks down the work into the concavity of the presser. This is particularly effective when comparatively heavy work, such as counter stiffeners, is being operated upon. It should be understood that the diagrammatic showing in Fig. 4 has been exaggerated so as to emphasize the action of the feed roll and presser in this particular. In the operation of the machine the feed roll 60 12 engages more or less all of that portion of the work between it and the presser 14, but the maximum pressure is localized along the line 26 at a distance from the edge of the work instead of substantially at the edge 65 of the work as has hitherto been the case.

If a piece of material has been inaccurately skived it may be desirable to pass it through the machine a second time. Should this be done with a feed roll of the shape above described, the thin edge of the material would be unsupported as this portion of the material passes over the coned portion of the feed roll. To overcome this difficulty yielding fingers 28 are arranged at the 70 coned portion of the roll in deep peripheral grooves between toothed disks 30 of which the feed roll 12 is built up. These yielding fingers are arranged to make up the normal longitudinal curve of the roll. Each finger is fastened by a clamp screw 32 and positioning pins 34 to a lever 36 which is mounted on a horizontal pivot 38 carried in a bracket 40 fixed to the feed-roll-supporting yoke-shaped head 42. The lever has a tail piece 44 which is held, when no work is in the machine, by a spring 46, situated in a recess in the bracket 40 and bearing against the underside of the lever 36, against an eccentric portion of a stud 48 rotatably mounted in the bracket 40. By rotation of the stud 80 the position of the fingers 28 relative to the periphery of the feed roll 12 may be adjusted, and the stud 48 may be locked in adjusted position by means of a set screw threaded into the bracket 40. The springs 85 46 yieldingly hold up the fingers 28, but, when a piece of material is being skived for the first time, the fingers easily are depressed by the material. On the other hand, they are upheld yieldingly with sufficient force 90 against an already skived piece to avoid the difficulties which would arise from a total lack of support at this part when skiving an already once-skived piece. In Fig. 5 is 95 shown a previously skived piece of work 105 which is being passed through the machine a second time, the thin, skived edge being supported by the yielding fingers 28.

The presser 14 is in this case a driven roll, the periphery of which is concave as 110 at 50 for the greater portion of its length and at that end of the roll nearest the horizontal axis 52 about which the roll is angularly adjusted the concave portion merges into a convex portion 54. The radius of the 115 longitudinal convexity is greater than the radius of the roll at this point. The center 52 of the lower longitudinal convex curve, as seen in Fig. 1, is slightly to the left of the vertical axial plane of the skiving knife. When viewing the machine as in Fig. 4, with the roll axis substantially horizontal and the roll at the height above the knife axis indicated in that figure, the point at which the 120 convex lower curve merges into the concave curve and the point at which the convex lower curve meets the knife edge are coincident and lie in the said vertical axial plane.

Angular adjustment of the roll to increase 125 the angle of the scarf will naturally move 130

the former of these points but the latter will remain undisturbed. Consequently, when the presser roll 14 is adjusted angularly about the axis 52 to vary the angle of the scarf, some point on the surface of the convex portion will always be at the desired uniform distance from the edge of the knife. This distance will determine the thickness of the extreme edge of the work after it has been skived. In the illustrative machine in the adjustment shown, this distance is substantially zero, and the margin of the work is skived down to a sharp edge. The distance may be regulated by adjusting the bar 16 vertically.

The roll 14 is bored to receive a stud 56 on which the roll rotates, which stud is clamped by a nut 58 on the end of the stud in one arm of a bracket 60. The other arm of the bracket at the opposite end of the roll, straddles the convex portion of the roll and forms a half bearing or seat for this portion to take the upward thrust on the roll. The bracket 50 has formed on it a rearwardly extending horizontal pin 62 having a bearing in the presser block 16, the axis of the pin coinciding with the axis 52. A thumb screw 64 threaded through a lug formed on the presser block 16 bears on the upper portion of the bracket 60, and a spring 65, attached at one end to a pin in the bracket and at the other end to a pin in the presser block 60, holds the bracket up to the screw. By rotation of the screw the bracket and roll may be adjusted about the axis 52 of the rearwardly extending pin 62 to vary the angle of the scarf. The convex end of the presser roll has formed axially in it a square recess to receive the square end of a driving rod 66, the other square end of which enters a square recess formed in a boss 68 on a spur-gear 70 having a horizontally extending shaft which is rotatably mounted in a bearing in the machine frame. The square ends of the rod and the square recesses are so formed as to provide universal driving connections. The spur-gear 70 meshes with a second spur-gear 72 which has a horizontally extending shaft rotatably mounted in a bearing formed in the machine frame below and parallel to the spur-gear shaft. The second shaft has on it a spiral gear 74 which is driven by a second spiral gear 76 mounted on the shaft which drives the feed roll of the machine. This shaft is situated below and at right angles to the two spur gear shafts.

Having thus described our invention, what we claim as new and desire to secure by Letters Patent of the United States is:

1. A machine of the class described, having in combination, a rotary skiving knife and means for feeding a piece of sheet material to the knife in such manner as to produce a beveled margin thereon, said

means comprising two members adapted to engage the margin of the material, one on one side and one on the other, the operative faces of said members being shaped to bend the margin into a curve and to exert maximum pressure upon the margin at a locality spaced from the edge of the material.

2. A machine of the class described, having in combination, a cylindrical knife, and a pair of members adapted to grip the work at its margin and feed it to the knife, said members being shaped to bend the margin into a curve and to exert their maximum gripping action at a locality spaced from the edge of the work.

3. A machine of the class described, having in combination, a cylindrical knife, a pair of rolls the operative faces of which are complementally shaped in such manner as to bend the margin of the work into a curve and to exert a maximum gripping action at a locality in the curve spaced from the edge of the work, and means for driving one of the rollers to feed the work.

4. A machine of the class described having, in combination, a cylindrical knife, a presser located outside the circle of the knife edge, and a cooperating feed roll longitudinally convex located inside said circle, said feed roll being formed with a ridge which extends nearer to the adjacent face of the presser than does any other portion of the roll.

5. A machine of the class described having, in combination, a cylindrical knife, a presser located outside the circle of the knife edge and having an operative face which is concave, and a cooperating feed roll longitudinally convex located inside said circle, said feed roll being formed with a ridge which extends nearer to the adjacent face of the presser than does any other portion of the roll.

6. A machine of the class described having, in combination, a cylindrical knife, a presser roll located outside the circle of the knife edge and having an operative face which is concave, and a cooperating feed roll longitudinally convex located inside said circle, said feed roll being formed with a ridge which extends nearer to the adjacent face of the presser roll than does any other portion of the feed roll.

7. A machine of the class described, having in combination, a cylindrical knife, a presser roll located outside the circle of the knife edge and having a concave operative face, a co-operating feed roll longitudinally convex located inside said circle, the feed roll having a shoulder located to press the work into the concavity of the presser roll with maximum force at a locality spaced from one end of the concavity, and means for rotating the rolls.

8. A machine of the class described, having in combination, a cylindrical knife, a presser located outside the circle of the knife and having a concave face presented to the edge of the knife, a co-operating feed roll located inside said circle and having a longitudinally convex portion merging into a conical portion, and means for driving the feed roll.
10. 9. A machine of the class described, having in combination, a cylindrical knife, a presser roll located outside the circle of the knife and having a concave face presented to the edge of the knife, a co-operating feed roll located inside said circle and having a longitudinally convex portion merging into a conical portion, and means for driving both of said rolls.
10. A machine of the class described, having in combination, a cylindrical knife, an edge gage, a presser, a feed roll having a groove in its periphery at that portion adjacent the edge gage, and a yielding member extending into the groove in position to support the previously skived edge of a piece of material.
11. A machine of the class described, having in combination, a cylindrical knife, an edge gage, a presser, a feed roll having grooves in its periphery at that portion adjacent the edge gage, and a series of yielding members extending into the grooves in position to support the previously skived edge of a piece of material.
12. A machine of the class described, having in combination, a cylindrical knife, a presser having a concaved body portion which merges into a convex portion, and means whereby the presser may be angularly adjusted about substantially the center of 40 curvature of the convex portion.
13. A machine of the class described, having in combination, a cylindrical knife, a presser roll the longitudinal contour of which is partly concave and partly convex, 45 and means whereby the roll may be angularly adjusted about the center of the curve of the convex portion which is adjacent the knife, whereby the distance between the convex portion and the knife remains unchanged in the various angular adjustments 50 of the roll.
14. A machine of the class described, having in combination, a cylindrical knife, a presser roll the longitudinal contour of 55 which is partly concave and partly convex, means whereby the roll may be angularly adjusted about the center of the curve of the convex portion which is adjacent the knife, whereby the distance between the convex portion and the knife remains unchanged in the various angular adjustments of the roll, and means for driving the presser roll.

In testimony whereof we have signed our names to this specification.

FRED RICKS.
ALFRED EDWARD RICHARDS.
